UNITED STATES PATENT OFFICE.

CLARENCE A. VAN DERVEER, OF MICHIGAN CITY, INDIANA, ASSIGNOR, BY MESNE ASSIGNMENTS, TO MIDLAND CHAIR & SEATING COMPANY, OF MICHIGAN CITY, INDIANA, A CORPORATION.

CHAIR.

1,078,810.

Specification of Letters Patent. Patented Nov. 18, 1913.

Application filed April 10, 1911. Serial No. 620,966.

To all whom it may concern:

Be it known that I, CLARENCE A. VAN DERVEER, a citizen of the United States, residing in Michigan City, in the county of Laporte and State of Indiana, have invented certain new and useful Improvements in Chairs, of which the following is a specification.

My invention relates particularly to chairs for use in parlor cars, and the primary object of my invention is to so construct chairs of this kind that they may be conveniently and quickly brushed and cleaned.

In carrying out my invention I provide a chair frame or body which may be mounted on a pedestal or other suitable standard and which supports a removable seat or cushion and a removable back. The chair frame is provided with a latch which engages the seat and holds it in place when in use and the posts at the back of the frame are so formed that the back which is moved vertically into engagement therewith is prevented from moving forward. The back is prevented from moving rearward by a cross-piece connecting the upper ends of the rear posts of the frame and by cleats on the frame with which engages a cross-piece connecting the lower ends of the side pieces of the back.

In the accompanying drawings, Figure 1 shows a side elevation of a chair embodying my improvements with parts broken away in order to better illustrate other parts. In Figs. 2, 3, and 4 some parts are broken away in order to show details of construction. Fig. 2 is a perspective view of the chair body. Fig. 3 is a perspective view of the back. Fig. 4 is a perspective view of the seat. Fig. 5 is a detail view showing on an enlarged scale the connection between the lower end of the back and the rear portion of the seat frame.

The seat frame A may be of any suitable construction and may be supported in any suitable way as by a pedestal B. The rear posts C which rise from the frame and are farther apart at their upper than at their lower ends, are preferably made rectangular in cross-section and are so secured to the seat frame that their inner front edges c are closer together than their rear edges c', thus forming a space between them which is nar-

rower at the front than at the rear. The upper ends of the posts are connected by a cross-piece D and the arms E which are connected at their rear ends with the posts C are supported near their front ends by posts F which rise from the frame A.

The seat cushion G has a frame of any suitable construction and is upholstered in any suitable way. The front rail g of this frame is provided with a recess h to receive a latch H carried by the front rail a of the seat frame A. The latch prevents the seat G from moving forward, its own weight holds the seat from rising, while rearward movement thereof is prevented by shoulders g' on the sides of the seat which abut against the front posts F.

The back consists of a frame comprising the side pieces I connected by a top piece J and a middle cross-piece J'. The side pieces I are wider at their upper portions than at their lower parts forming shoulders i adapted to rest on the tops of the posts C, and the side pieces I are so spaced and so arranged that they will fit snugly between the posts C. The outer front edges i' of the side pieces I are closer together than the outer rear edges i'' and in order to place the back in place it is necessary to slide it downward between the posts C in front of the cross-piece D. By this arrangement the back can not move forward and the cross-piece D serves to prevent rearward movement of the middle portion of the back. In order to prevent rearward movement of the lower end of the back, I attach a cross-piece K to the lower ends of the side pieces I which is adapted to engage cleats L secured to the rear portion of the seat frame between the rear posts C. Thus it will be seen that the back and seat can be very easily detached from the chair frame, brushed and cleaned and very quickly replaced. The back can be easily lifted and separated from the chair frame without removing screws, bolts, or other fastenings and the seat can be drawn forward and separated from the frame after the latch H has been depressed.

All exposed parts of the chair except the pedestal may be upholstered as indicated.

I claim as my invention:

A chair, comprising a frame having rear posts rectangular in cross section with a

space between them narrower at the front than at the rear, a cross-piece connecting the upper ends of the posts at their rear edges, horizontally arranged cleats between the lower ends of the posts, and a back comprising side pieces fitting snugly between the rear posts of the chair in front of the cross-piece connecting the upper ends of the posts

and having a cross-piece at the bottom engaging the cleats.

10

In testimony whereof, I have hereunto subscribed my name.

CLARENCE A. VAN DER VEER.
